ORNAMENTED WALLBOARD FOR OUTSIDE
WEATHERPROOFING

Leslie S. Odell, Montreal, Quebec, Canada, assignor to Bird & Son, Inc., East Walpole, Mass.

Application December 31, 1931, Serial No. 584,110

9 Claims. (Cl. 20—5)

This invention relates to the manufacture and use of wall board coverings for outside weatherproofing purposes and has particular reference to sectional coverings of the ornamental granular surface type disclosed in my co-pending application Serial No. 584,109, filed Dec. 31, 1931.

The principal object of the present invention is to enhance the appearance and weatherproofing qualities of the wall board covering by improving the construction and arrangement of the joints formed between the meeting ends of horizontally aligned sections of the covering.

With the exception of certain specific improvements hereinafter described the wall board covering material provided in accordance with this invention is essentially the same as that set forth in the co-pending application previously referred to. It comprises a plurality of interfitting sections, each having a fibrous base, a covering strip of asphalt impregnated felt, and a weather resistant surface composed of differently colored particles of granular material applied to the outer surface of the felt to present areas of contrasting colors simulating a definite ornamental pattern such as a brick, stone, tile or other ornamental surface. When sections of the improved covering material produced in accordance with this invention are assembled on the surface to be covered, the upper and lower edges of adjacent superposed sections are fitted together with tongue and groove connections to form horizontal joints of the type described in my co-pending application, but the vertical edges of the sections instead of being cut square as described in said co-pending application are formed in a particular manner to increase the waterproofing characteristics of the vertical joints and to produce between the pattern surfaces of horizontally aligned sections irregular lines of juncture which follow the lines of the pattern in such a way as to avoid bisecting those colored areas of the granular pattern which would tend to emphasize the lines of juncture if seen in contrast therewith.

Other objects and advantages of the present invention will be more readily understood from the following detailed description and accompanying drawing wherein

Figure 1 is a view in side elevation of a plurality of complementary sections of ornamental wall board constructed in accordance with this invention. In this view the complementary sections are shown in horizontal alignment but in separated relation.

Figure 2 is a view similar to Fig. 1, but show-

ing the sections of the wall board covering in assembled relation.

Figure 3 is a perspective view of one end of one of the wall board sections looking towards the ornamented surface of the section.

Figure 4 is a perspective view of the opposite end of one of the wall board sections looking towards the side opposite that covered by the ornamental pattern.

Figure 5 is a vertical sectional view through a plurality of wall board sections constructed in accordance with this invention. In this view the sections are shown in vertical alignment but in disassembled relation.

Figure 6 is a view similar to Fig. 5 but showing the superposed sections assembled together and secured in place on the surface to be covered.

As shown in the drawing, each section of the covering material comprises a comparatively rigid base 11 composed of paper or other fibrous material and made in accordance with the practice usually followed in the manufacture of ordinary wall board. The base is provided at one side with an adherent asphalt impregnated strip 13 made of felt or other suitable absorbent material, said strip being held in place by asphaltum 12 or the like. At its outer surface the covering strip or felt 13 is protected by a weather resistant surface composed of differently colored particles of ground stone, slate or other granular material arranged to simulate a definite ornamental surface pattern. In the present instance the granular particles are arranged to present brick colored areas 14 separated by mortar colored areas 15 but it will be manifest that these particles may be colored and arranged in various other ways to simulate a stone or tile surface or any other desired type of ornamental pattern.

When applied to cover a given surface the sections of the covering material are preferably assembled on said surface in parallel rows with the component sections of each row disposed in edge to edge relation with respect to each other and adjacent sections of the adjoining rows.

The intermediate sections of each row are represented by the section marked X while the terminal sections of each row are represented by the sections marked X'. The base 11 of each intermediate section X presents diagonal end edges 11a and 11b adapted to engage with correspondingly inclined base edges of adjacent sections contained in the same row. The ornamental covering strip 13 of each intermediate section X has one end extended beyond the base edge 11a to form a projecting tab 13a terminating in an

irregular or stepped edge 13b. The opposite end of said strip 13 also terminates in a similar but reversely stepped edge 13c but in this case the edge 13c is spaced inwardly from the adjacent end edge 11b of the base. The portion 11c of the base which is thus exposed between its edge 11b and the edge 13c of the felt covering is preferably provided with an adhesive coating of asphaltum or other bituminous waterproofing compound.

On referring to the assembly shown in Fig. 2, it will be noted, with respect to sections contained in the same row, that the projecting felt tab 13a at one end of each section overlies the exposed base surface 11c of an adjoining section and has its stepped edge 13b fitted against the complementary stepped edge 13c of the felt strip covering said adjoining section. These stepped edges 13b and 13c of the felt strips 13 are so arranged that the resulting line of demarcation between the sections of the granular surface pattern follow along certain contiguous longitudinal and transverse lines of the mortar colored areas 15 and are blended with these areas in such a manner as not to be seen in contrast therewith or in contrast with the brick colored areas 14. By providing stepped or irregular lines of demarcation between adjoining sections of the horizontally aligned granular surface pattern and by causing these irregular lines to follow only the mortar lines of the pattern, these lines of demarcation are so blended with the lines of the pattern itself as to be scarcely distinguishable at a relatively short distance. The terminal sections X' of the covering material contained in each row are cut square at their outer ends as indicated at 17 in Fig. 2. At the inner end of each terminal section X the felt covering may be extended beyond the adjacent end of the base in the form of a projecting tab 13a having a stepped edge 13b or it may terminate in a stepped edge 13c spaced inwardly from the edge of the base depending upon the construction of the mating end of the intermediate section.

The lower edge of each section of the covering material is provided with a groove 18 lying between the inner and outer surfaces of the section and adapted to receive a tongue 19 projecting upwardly from the upper edge of the next lower section. The groove 18 is formed by cutting away the outer lower edge portion of the base 11, the outer wall of the groove being formed by the projecting portion 13d of the felt strip 13 and the inner wall of the groove being formed by the projecting portion 11d of the base 11. The tongue 19 at the upper edge of each section is formed by cutting away the inner upper edge portion of the base 11 to provide a recessed portion 11e adapted to receive the projecting portion 11d at the lower edge of the base of the next upper portion. The upper edge 13e of each felt strip is positioned below the plane of the horizontal shoulder formed by the bottom of the recess 11e. The purpose of this is to permit fastening nails to be driven through the intervening portion of the base as indicated at 21. When complementary sections are assembled in the superposed relation shown in Fig. 6 the nails 21 passing through the upper portion of each section are concealed by the overlapping felt projection 13d of the next upper section, this felt projection 13d being made of sufficient length to engage with the upper edge 13e of the felt strip of the next lower section so that the outer surface of each

tongue 19 and the portion of the base through which the nails 21 are passed are effectively concealed. In this assembly it will also be noted that the lower edge of each section of the covering material is held in place without the use of 5 nails since the base projection 11d is confined beneath the tongue 19 of the nailed down upper edge of the next lower section. That portion of the base of each section which is exposed beyond the upper edge 13e of the felt strip is preferably 10 provided with a waterproofing coating of asphalt or other adhesives.

Having thus described my invention, what I claim is:—

1. Weatherproofing material comprising a plurality of complementary sections adapted to be joined together in edge to edge relation, each section including a comparatively rigid base, a waterproof felt covering sheet applied to one side of said base and a weather resistant surface composed of differently colored particles of granular material embedded in asphalt at the outer side of said sheet, said particles being arranged to present contrastingly colored areas simulating a 25 definite ornamental surface pattern, the end edges of the felt covering sheets of engaging sections being shaped to meet along an irregular line of demarcation blending with certain lines of the pattern in such manner that the joints between the felt sheets are thereby rendered substantially inconspicuous. 30

2. Weatherproofing material comprising a plurality of complementary sections adapted to be joined together in edge to edge relation upon the 35 surface to be covered, each section comprising a wall board base and a covering sheet, such as felt, applied to one side of the base and having its outer surface covered by an ornamental surface pattern composed of differently colored particles of granular material arranged to present brick colored areas separated by intervening mortar colored areas, the end edges of the pattern carrying sheets of engaging sections being shaped and arranged to meet along an irregular 40 line of demarcation following contiguous mortar colored areas of the pattern without bisecting the brick colored areas. 45

3. Weatherproofing material comprising a plurality of complementary sections adapted to be 50 joined together in edge to edge relation upon the surface to be covered, each section comprising a comparatively rigid base of fibrous material and a strip of felt secured to the outer side of the base and provided with a weather resistant outer surface composed of differently colored particles of granular material arranged to present contrastingly colored areas simulating a definite ornamental surface pattern, the ornamented felt strip of each section being extended at one end 60 beyond the corresponding end of its attached base to meet the adjacent end of the felt strip of an adjoining section along an irregular line of junction lying within the length of the base of said adjoining section. 65

4. Weatherproofing material comprising a plurality of asphalt impregnated felt strips adapted to be butted together in edge to edge relation and presenting edges of irregular contour at the meeting ends of adjacent sections, each section having a rigid base abutting the bases of similar sections and being provided on its outer surface with differently colored granular particles arranged to simulate a definite pattern, certain lines of 70

which follow and blend with the irregular edges at the meeting ends of the felt strips.

5. Weatherproofing material of the character described comprising a rigid wall board base, a covering sheet of waterproof felt adhesively secured to one side of said base, said sheet having a weather resisting surface comprising differently colored particles of granular material embedded in asphalt at the outer side of the sheet and arranged to present a plurality of courses of brick colored areas, the component brick colored areas of each course being separated from each other and from the brick colored areas of adjacent courses by intervening mortar, colored areas of the granular particles, the transverse mortar colored areas between the brick colored areas of each course being staggered with respect to the transverse mortar colored areas of the adjacent course or courses, the end edges of the felt covering strip being stepped to provide an irregular edge which extends across the width of the sheet along the lines of certain of the transverse and longitudinal mortar colored areas of the granular pattern.

6. Weatherproofing material comprising a wall board base, a covering sheet of waterproof felt applied to one side of said base, said sheet being cut to provide stepped end edges, one of said edges being spaced inwardly from the adjacent edge of the base and the other being projected beyond the remaining edge of the base, said felt strip having at its outer side a weather resisting surface comprising differently colored particles of granular material embedded in asphalt, said particles being arranged to provide several courses of brick colored areas and intervening mortar colored areas, certain transverse and longitudinally extending mortar colored areas being located at and contiguous with correspondingly extending portions of the stepped edges of the felt sheet.

7. A section of siding material comprising a stiff base presenting parallel obliquely inclined end edges, a waterproof covering sheet applied to one side of said base and presenting stepped end edges, one end edge of said sheet being spaced inwardly from the adjacent end edge of the base

and the remaining end edge of the sheet being projected beyond the remaining end edge of the base and differently colored particles of granular material covering the outer surface of the sheet and arranged to present pattern lines coinciding with the edges of the sheet so as to blend with and conceal the joint lines formed by and between the meeting edges of the felt covering sheets of adjacent sections when a plurality of said sections are assembled in edge to edge relation on the surface to be covered.

8. A section of siding material comprising a stiff base presenting parallel obliquely inclined end edges, an inner horizontal recess adjacent its upper edge and an outer horizontal recess adjacent its lower edge; a covering sheet applied to the outer surface of the base with the upper edge of the sheet positioned below the bottom wall of the inner recess and the lower portion of the sheet overlying the outer recess and projecting beyond the lower edge of the base, one end edge of said sheet being stepped and spaced inwardly from the adjacent end edge of the base and the remaining end edge of said sheet being stepped and projected beyond the remaining end edge of the base, and differently colored particles of granular material on the outer surface of the sheet presenting pattern lines coinciding with the edges of the sheet so as to blend with and conceal the joint lines formed by and between the meeting edges of the covering sheets of adjacent sections when a plurality of said sections are assembled in edge to edge relation on the surface to be covered.

9. A siding panel or the like, comprising a rigid fiber board base, a superstructure of asphaltic roofing secured to one face of said board, said superstructure having side edges serrated to represent the staggered ends of courses of brick, said superstructure being offset with respect to said board so that the lower edge and an entire side edge thereof are outside of the contour of said board.
